FIG 4

FIG 5

FIG 6

FIG. 8

FIG. 9

FIG. 7

FIG. 1 is a perspective view of a combined reel and holder with rod and carrying strap for fishing, kite flying or similar use which embodies my design shown carried by a carrying strap on a wearer, the wearer being shown for illustrative purposes;

FIG. 2 is a side elevational view thereof showing the rod in its stored position in the handle, the showing of the rod broken away in this figure and elsewhere indicating indeterminate length;

FIG. 3 is another side elevational view thereof shown in use for kite flying, the kite and string being shown for illustrative purposes;

FIG. 4 and 5 are, respectively, front and rear elevational views thereof;

FIG. 6 is an opposite side elevational view thereof showing the rod in an operative position at the front of the holder;

FIG. 7 is a perspective view thereof;
FIGS. 8 and 9 are, respectively, top and bottom plan views thereof.

I claim:

The ornamental design for a combined reel and holder with rod and carrying strap for fishing, kite flying or similar use, as shown and described.
